UNITED STATES PATENT OFFICE.

SAMUEL ADOLPHUS CLARK, OF SEATTLE, WASHINGTON.

TABLE OPENING AND CLOSING DEVICE.

1,307,808.

Specification of Letters Patent. Patented June 24, 1919.

Application filed May 31, 1918. Serial No. 237,514.

To all whom it may concern:

Be it known that I, SAMUEL ADOLPHUS CLARK, a citizen of the United States, residing at Seattle, in the county of King and State of Washington, have invented certain new and useful Improvements in Table Opening and Closing Devices; and I do hereby declare the following to be a full, clear, and exact description of the invention, such as will enable others skilled in the art to which it appertains to make and use the same.

This invention relates to extension tables and the primary object of the invention is to provide an improved means for opening and closing the table, so as to eliminate the inconveniences usually associated with opening and closing extension tables.

Another object of the invention is to provide an improved extension table in which the sections thereof carry inwardly extending rack bars between which is positioned a pinion carrying an operating shaft, whereby upon operation of the shaft, the sections through the medium of the pinion and rack bars will be moved toward or away from each other according to the direction of rotation of the shaft.

A further object of the invention is to provide an improved means for connecting the pinion to the table, so as to prevent sagging of the table sections, when the table is in its extended position.

A still further object of the invention is the provision of an extension table having guide ways secured to the under surface thereof, in which is slidably mounted a frame, which braces the table when the table is in its extended position and carries an operating member arranged to operatively engage suitable means rigidly connected to each of the table sections.

A still further object of the invention is to provide an improved table of the above character, which is durable and efficient in use, one that is simple and easy to manufacture, and one that can be placed upon the market at a reasonable cost.

With these and other objects in view the invention consists in the novel construction, arrangement and formation of parts, as will be hereinafter more specifically described, claimed and illustrated in the accompanying drawing, forming a part thereof in which:

Figure 1 is a side elevation of the table

top constructed in accordance with my invention,

Fig. 2 is a front elevation of the table top, Fig. 3 is a fragmentary bottom plan view 60 of the table showing the improved attachment applied thereto and showing parts of the same in section,

Fig. 4 is a detail cross section taken on the line 4—4 of Fig. 2,

Fig. 5 is a detail cross section taken on the line 5—5 of Fig. 4, and

Fig. 6 is a detail section taken on the line 6—6 of Fig. 4.

Referring to the drawings in detail, 70 wherein similar reference numerals designate corresponding parts throughout the several views, the numeral 1 generally indicates the improved device, which is adapted to be applied to the ordinary or any preferred type of extension table 2, which includes the sections 3 and 4. The section 3 is provided with guide strips 5 secured to the under surface thereof, which project outwardly toward the section 4, and forms 80 means for guiding the sections in their closed position.

The sections 3 and 4 of the table 2 are provided with a pair of spaced L-shaped guide strips 6 which are in direct alinement 85 with each other and are adapted to receive a substantially rectangular sliding frame 7, which includes relatively long side walls 8 and the end walls 9. The sliding frame 7 is slidably mounted in guide walls 6 and forms 90 means for bracing the table to prevent sagging thereof when the sections 3 and 4 are in their extended position. The side walls 8 of the sliding frame 7 have secured to their inner surface at the central portion 95 thereof downwardly extending supporting arms 10 in which is rotatably journaled the operating shaft 11, the terminals of which

extend to the side edges of the table top 1 and are provided with operating handles of 100 suitable configuration 12, whereby the shaft may be readily rotated. The upper surfaces of the arms 10 are connected together by a suitable bracing member 13 which is adapted to abut the lower surface of the sections 105 3 and 4. A pinion 14 is secured to the shaft 11 by means of a key 15 or the like and is positioned between the arms 10 and is adapted to mesh with the upper and lower rack bars 16 and 17. The upper rack bar 16 110 is secured at its outer end to the lower surface of the section 3 by suitable spacing

brackets 18 and the rack bars are arranged to project inwardly toward the section 4. The rack bar 17 is secured at its outer end by a suitable fastening element to a rectangular shaped bracket 19, which is secured by suitable fastening elements 20 to the section 4. A spacing plate 21 is arranged between the bracket and the section 4, so as to space the bracket therefrom, to permit the same to 10 engage the upper surface of the rack bar 16 to form a bearing surface for the same. A guide strip 22 is secured at the central portion thereof to the arms 10 and forms a suitable rest for the rack bar 17. An upward standing lug 23 is formed on one end of the guide strip 22 and forms means for limiting the opening movement of the sections 3 and 4.

In operation of the improved device, when 20 it is desired to open the table, the shaft 11 is rotated by means of one of the handles 12 which will in turn rotate the pinion 14, and thereby force the rack bars 16 and 17 in opposite directions, which will force the table 25 sections 3 and 4 apart. When it is desired to close the table, the shaft 11 is rotated in the opposite direction.

In practice, I have found that the form 30 of my invention, illustrated in the accompanying drawings and referred to in the above description, as the preferred embodiments, is the most efficient and practical; yet realizing the conditions concurrent with the adoption of my device, I desire to emphasize 35 the fact that various minor changes in detail of construction, proportion and arrangement of parts may be resorted to, when required, without sacrificing any of the advantages of my invention as set forth.

40. What I claim as new is:

1. An extension table comprising a pair of sections, alined guide ways carried by each section extending along the central longitudinal axis thereof, a substantially rectangular open frame slidably mounted in the guide ways, depending arms carried by

the central portion of the frame, a shaft rotatably carried by the arms, a rack bar carried by each section and arranged in superimposed relation; a pinion keyed to the shaft 50 and arranged to engage the rack bars, and operating handles formed on the terminals of the shaft.

2. An extension table comprising a pair of sections, alined guide ways carried by the sections, a substantially rectangular frame slidably mounted in the guide ways, depending arms carried by the central portion of the frame, a shaft rotatably carried by the frame, and the terminals of the shaft extending to the side edges of the table, a rack bar carried by each section and arranged in superimposed relation to each other, a pinion keyed to the shaft and arranged between the depending arms and intermeshing with the rack bars, operating handles carried by the terminals of the shaft, and a guide strip carried by the lower ends of the arms and arranged to slidably receive the lower rack bar.

3. An extension table comprising a pair of sections, alined guide ways carried by each section, a substantially rectangular frame slidably mounted in the guide ways, depending arms carried by the central portion of the frame, a shaft rotatably carried by the arms, super-imposed rack bars carried by the sections, a pinion keyed to the shaft and arranged to operatively engage the rack bars, operating handles carried by the terminals of the shaft, a guide strip carried by the free ends of the arms and arranged to slidably receive the lower rack bar, and a lug carried by one end of the guide strip.

In testimony whereof I affix my signature in presence of two witnesses.

SAMUEL ADOLPHUS CLARK.

Witnesses:

W. A. HUTTON,
H. A. BERNARDO.
